19 Claims. (Cl. 123—65)

1

Our invention has for its object internal combustion and the like engines of the two stroke type, the scavenging and the movements of the load being executed under equicurrent conditions throughout the cylinder.

In two stroke engines of standard type, the filling of the cylinders is obtained by loading them through a stream of fresh gases blown into same for exhausting the burnt gases. It is thus necessary to incorporate a pumping system so as to suck in the fresh gases and to deliver them into the cylinder inside which they unavoidably come into contact with the residual gases that have already expanded through their laminating passage inside the exhaust ports under delivery pressure while in close contact with the fresh gases. Said contact between two gases, even of a very short duration, can but stir the masses with one another, which leads on one hand to losses of fresh gases exhausted with the burnt gases and on the other hand to a sort of poisoning of the load through the burnt gases admixed therewith.

The suction and exhaust means provided for such conventional engines do not allow contemplating any other solution to the problem.

Our invention has for its object to bring a deep modification to the standard technique, the movements of the load being assured through an extremely rapid opening and closing of the large sized suction and exhaust ports so as to provide an immediate exhaust of the residuary gases at one end of the cylinder under the action of their spontaneous expansion. By reason of their dynamic energy the mass of exhausted gases sucks in energetically the gases forming the load through the suction ports that have been uncovered in the meantime at the other end of the cylinder. The rapid closing of the exhaust ports stops then the passage of this current of gases arriving at full speed and causes the latter to settle over a height corresponding to the volume and speed of said current while the closing of the suction ports opposes the retrogression of the gases and produces an excess pressure inside the cylinder. The overload increases by reason of the acceleration of the engine speed and may reach considerable values.

Whereas in engines of the fuel injection type, the adjustment allows an excess passage of air,

2

the case is not the same in engines where the explosive load is submitted to a preliminary stirring and cannot be lost. In this latter case, the adjustment may be executed in a manner such

5 that the burnt gases and the load move with an intermediary zone of depression between them that is cut in vacuo through a closing of the exhaust which removes the possibility of a loss of rich gases without changing the conditions of admission and delivery for the engine.

We have shown by way of example and by no means in a binding sense, various embodiments of our invention. In said drawings:

Fig. 1 is a sectional view of an engine incorporating the principle of our invention.

Fig. 2 illustrates a modification thereof.

Fig. 3 shows on a larger scale and cross sectionally the upper part of an engine with an overhead valve gear.

20 Fig. 4 is a graph showing the transmission gear for every 10° of the revolution of the eccentric.

Fig. 5 is a graph giving out the movements of the driving piston for every 10° of said revolution.

25 Fig. 6 is a diagram corresponding to the graphs of Figs. 4 and 5 for two different adjustments.

Fig. 7 illustrates a set of control links operating in the same plane.

30 Figs. 8 and 9 illustrate modifications of this arrangement of control links.

Fig. 10 is an elevational view of a cylinder sleeve with two slide valves controlled by a compensation bar.

35 Fig. 11 is a diagrammatic showing of the control means for a radial engine.

Figs. 12 and 13 are diagrammatic illustrations in side and elevational views of the control mechanism driven by a crankshaft provided with two sleeves and with further links.

40 Fig. 14 is an elevational view of a cam-operated control system.

In the embodiment illustrated in Fig. 1 the engine includes primarily an engine unit 1 with its crankcase 2, its water jacket 3, its exhaust pipe 4, its admission pipe 5 and its head 6 engaging the cylinder down to the upper level of the upper ports provided for the passage of the gases.

The crankshaft 7 and its connecting rod 8 are operatively connected with the piston 9 slidably carried inside the stationary sleeve 10. Said

sleeve is provided with upper ports 11 and with lower ports 12 which latter are in register with a point occupied by a point of the head of the driving piston just above the lower dead center of the piston stroke.

The sleeve 10 is enclosed by the slide valve 13 the ports 14 and 15 in which are adapted to move respectively over the ports 11 and over the ports 12 in the sleeve under the action of a mechanism operated by an eccentric 16 driven by the engine and including a link connection 17-18 between said eccentric and the slide valve, said link connection pivoting round the spindle axis 19. The transmission of the sliding movement to the slide valve 13 for covering and uncovering the ports 11 and 12 is obtained through cooperation with the link 20 controlling said slide valve in either direction, the direction of the movement of the slide valve being always opposed to that of the driving piston.

The first slide valve 13 is enclosed inside a further slide valve 21 provided with ports 22 crossing the ports 14 for registering at a predetermined moment of their movement with the ports 11 and simultaneously with the ports 14, the movement of said slide valve 21 being controlled by a bar 23 connected with both slide valves 13 and 21 for providing their movements in opposite directions. These opposed movements are obtained through the rods 24 and 25 while the head of the piston 9 moves in a direction opposed to that of the ports 15 in the slide valve 13 so as to uncover the admission ports 12 in co-operation with the latter ports.

This arrangement of two slide valves moving simultaneously in opposite directions provides openings of the same size as a single slide valve but it produces their covering and uncovering in half the time required with a single slide valve operating with equal lengths of stroke in either direction, while allowing the possibility of providing the desired shifting for the timing and duration of exhaust and admission.

Referring to Fig. 2, it is apparent that it is similar to Fig. 1 with the difference that the slide valves 13 and 21 are housed inside the engine cylinder, the slide valve 13 taking the place of the cylinder lining 10 and serving as a bearing for the driving piston 9 without anything being changed in the closing operation performed by it. Furthermore the slide valve 21 is controlled by a projection 26 controlled in its turn by a rod 27 while the connections disclosed hereinabove as provided between the slide valves 13 and 21 are cut out as illustrated.

As illustrated in Fig. 3, the timing gear is carried in overhead relationship with the engine so as to locate next to it, the compact arrangement of Fig. 1 including the eccentric 16, a pivoting link system 17-18 connected with the stationary pivot 19' and the link 20' acting on the compensating bar 23 for transmitting the movement to the slide valve 21 and to the slide valve 13 through the agency of the corresponding rods 25 and 24.

The operation of the three embodiments will appear in the graphs of Figs. 4 and 5 and in diagram of Fig. 6. Thus Fig. 4 shows for each 10° of the revolution of the eccentric 16 the location of the mechanical system and chiefly of the compensating bar provided for the control of the slide valves.

Fig. 5 illustrates for every 10° of the movement the location of the driving piston for the portion

of the stroke thereof corresponding to the covering and uncovering of the lower ports.

Fig. 6 is a diagram illustrating clearly the practical consequences of the graphs of Figs. 4 and 5 with two different timings of the opening of the exhaust through the upper ports, and of the admission through the lower ports; the curves show the movements in opposite directions of the operating moving ports.

The timing of the admission through the lower ports corresponds to the drawing in solid lines while the other timing with admission through the upper ports and exhaust through the lower ports corresponds to the drawing in dot and dash lines. The reference numbers given are the same as those of the ports in the stationary sleeve 10 of Fig. 1 while the hatched parts 11²-12³ correspond to the capacities of the exhaust and the hatched parts 12² and 11³ correspond to the capacities of the admission, the engine being supposed to have its exhaust built in overhead relationship.

Within the scope of the invention, it is possible for instance to cut out the slide valve 21 and the transmission means controlling it in any of Figs. 1, 2 and 3 so as to provide a single covering means for the upper ports while the lower ports remain controlled by double covering means of which one is actually formed by the moving piston.

It is possible also for the driving piston to provide alone for the control of the lower ports while one or two covering members or slide valves control the upper ports.

These various combinations are applicable with advantages that are similar to those provided by the embodiments illustrated, chiefly in the case of engines with small or average sized cylinder capacities in accordance with the cycle of operations disclosed by the diagrams.

Fig. 7 illustrates on a larger scale and in plan view a system of links of the type illustrated in Fig. 1 together with their controlling and connecting means operating in a same plane.

Figs. 8 and 9 illustrate a combination of the system of links and control means operating in several planes for actuating two slide valves moving in opposite directions as in the case of Figs. 2 and 3.

Fig. 10 shows a cylinder sleeve 10 provided with two slide valves 13 and 21 attached respectively at 13' and at 21'. Said points 13' and 21' are connected through rods 24 and 25 to two projections defining a compensator bar 23, which projections are secured to the rocking shaft 19 controlled by a set of links not illustrated.

In Fig. 11, we have illustrated a control system for an engine the cylinders of which are arranged in radial relationship while the different slide valves are actuated by a common eccentric 16 secured to a shaft 30 forming an extension of the crankshaft, the link system of each cylinder being pivotally secured to a ring 31 controlled by the eccentric 16 and held in a stable position through the eccentric 16³ connected with the projection 32 on said ring 31. It is thus apparent from inspection of Fig. 11 how the position of the links lies for the seven stages of a cycle extending a little over 51° of the revolution of the crankshaft.

This arrangement is applicable as well of course to all engines with a radial sectional arrangement.

A control mechanism for the slide valve or valves includes further members with the object either of shifting the moments of acceleration or

of adjusting the magnitudes governing the strokes and accelerations or else of obtaining any other modification in accordance with the requirements of the cycle of operation or the constitution of the engine. This is shown in Figs. 12 and 13 where the crankshaft is provided with a second crank of eccentric 33 acting on the connecting rods 34, 35 of which the latter is inserted between the connection with the links 17, 18 and the connecting rod 20 leading to the slide valves.

Turning to Fig. 14 said figures show a cam-operated control mechanism ensuring a positive drive in both directions.

To the shaft 36 are secured in different planes cams 37 and 38 of which the former engages the roller 39 while the second cam engages the roller 40. The two rollers are rotatably carried by the compensator member 23 through the agency of a rocking shaft 35 controlling the slide valves 13 and 21 not illustrated through the connections provided by the rods 24 and 25.

During the period during which the rollers 39 and 40 are in contact with parts of the cams 37 and 38 co-axial with the shaft 36, the movement of the slide valves is zero, said movement being started suddenly through eccentric portions of said cams. The whole cycle of operation of the cams is executed without either of them moving theoretically out of contact with reference to its rollers. This arrangement may lead to an uncovering of the ports similar to that appearing in Fig. 6.

From the preceding disclosure, it is apparent that the port covering member operating singly controls the corresponding ports at a speed that may be sufficient for operation with either rate of operation of the ports, while retaining all the advantages described for certain categories of engines whereas for other categories, it is necessary to resort to double covering members because they may double the speed of covering and of uncovering the passages for the gases.

Without unduly widening the scope of the invention as defined in accompanying claims, it is possible to incorporate the above arrangement of slide valves and of a piston to double acting engines or the like, both for exhaust and for admission and the shifting of the timing may be obtained without any shifting of the relationship between the crankpins of the two driving crankshafts to be considered; the movement of the closing slide valves may be operated axially of the cylinder or else it is possible to make them assume a tacking movement with reference to said cylinder.

The arrangement disclosed is also applicable for other arrangements of the cylinders with an engine of radial or radial section type, also with engines of the double or multiple acting type or else having moving cylinders arranged in square or the like formation. The connections between the control means and the slide valves may be performed also through the head of each cylinder; any further arrangements of links and transmission means and relays may be inserted between the control means and the slide valves; the slide valves may be constituted by interconnected sections or else these sections may be controlled by a crankshaft provided with a plurality of cranks or by a plurality of crankshafts; the control and transmission means may be secured to a number of stationary points and in brief any combination may be made between the elements described and disclosed.

Obviously our invention has been described as 75 for uncovering and covering at a high speed said

illustrated by way of a mere indication and by no means in a limiting sense and numerous modifications may be brought to the details thereof without unduly widening thereby the scope of the invention as defined in accompanying claims.

What we claim is:

1. In a two stroke internal combustion and the like engine, the combination of a cylinder provided at each end with two series of ports adapted respectively to serve as admission ports and as exhaust ports, the upper series of ports being provided at the upper end of the cylinder and the lower series opening substantially at the lower end of the combustion chamber in the cylinder, a driving piston adapted to reciprocate inside the cylinder between an upper dead point and a lower dead point substantially in register with the lower series of ports, a slide valve slidably engaging one of the surfaces of the cylinder and provided with a series of ports adapted to register with the upper series of ports in the cylinder, a linkwork connected with the slide valve for producing a sliding movement of the latter over the cooperating surface of the cylinder, an eccentrically operating member controlling the linkwork to constrain the slide valve to operate cyclically, the cyclic operation of the valve including a long period of very small oscillations providing for the covering of the upper series of ports in the cylinder and then a very highly accelerated movement for uncovering and then covering again said upper series of ports in the cylinder while the valve moves at high speed and produces thus an opening of the upper ports with a large cross-sectional passage during a very short time, the cycle terminating with the return into the port covering position, the driving piston being adapted to cover and uncover the lower series of ports in the cylinder, a lag being provided between the uncovering of the upper series of ports and that of the lower series of ports in the cylinder.

2. In a two stroke internal combustion and the like engine, the combination of a cylinder provided at each end with two series of ports adapted respectively to serve as admission ports and as exhaust ports, the upper series of ports being provided at the upper end of the cylinder and the lower series opening substantially at the lower end of the combustion chamber in the cylinder, a driving piston adapted to reciprocate inside the cylinder between an upper dead point and a lower dead point substantially in register with the lower series of ports, a slide valve provided with two series of ports adapted to register respectively with the upper and with the lower series of ports in the cylinder, a linkwork connected with the slide valve for producing a sliding movement of the latter over the cooperating surface of the cylinder, an eccentrically operating member controlling the linkwork to constrain the slide valve to operate cyclically, the cyclic operation of the valve including a long period of very small oscillations providing for the covering of the upper and lower series of ports in the cylinder and then a very highly accelerated movement for uncovering and then covering again said upper and lower series of ports in the cylinder while the valve moves at a high speed and produces thus an opening of the upper ports with a large cross-sectional passage during a very short time, the cycle terminating with the return into the port covering position, the driving piston cooperating with the lower series of ports in the slide valve.

lower series of ports in the cylinder through a movement that is simultaneous with and in the opposite direction with reference to that of the slide valve in front of said lower series of ports, a lag being provided between the uncovering of the upper series of ports and that of the lower series of ports in the cylinder.

3. In a two stroke internal combustion and the like engine, the combination of a cylinder provided at each end with two series of ports adapted respectively to serve as admission ports and as exhaust ports, the upper series of ports being provided at the upper end of the cylinder and the lower series opening substantially at the lower end of the combustion chamber in the cylinder, a driving piston adapted to reciprocate inside the cylinder between an upper dead point and a lower dead point substantially in register with the lower series of ports, two slide valves provided each with a series of ports adapted to register with the upper series of ports of the cylinder, said slide valves being arranged to either side of the cylinder wall and being adapted to move simultaneously and in opposite directions in register with the upper ports in the cylinder for covering and uncovering same through their cooperation, a linkage connected with at least one slide valve, an eccentric member positively controlling said linkage, a rocking lever operatively connecting the two slide valves together, said arrangement of the linkage, eccentric and rocking lever being adapted to constrain the slide valves to move in opposite directions when closing the upper series of ports in the cylinder and to operate cyclically, the cycle of operation including a long period of short oscillations while the slide valve closes the upper series of ports in the cylinder, after which the slide valves assume a high acceleration for uncovering and then covering again said upper series of ports in the cylinder while the valves move at high speed and produce thus an opening of the upper ports with a large cross-sectional passage during a very short time, the cycle terminating with the return into the port covering position, the driving piston being adapted to cover and uncover the lower series of ports in the cylinder, a lag being provided between the uncovering of the upper series of ports and that of the lower series of ports in the cylinder.

4. In a two stroke internal combustion and the like engine, the combination of a cylinder provided at each end with two series of ports adapted respectively to serve as admission ports and as exhaust ports, the upper series of ports being provided at the upper end of the cylinder and the lower series opening substantially at the lower end of the combustion chamber in the cylinder, a driving piston adapted to reciprocate inside the cylinder between an upper dead point and a lower dead point substantially in register with the lower series of ports, two slide valves provided each with a series of ports adapted to register with the upper series of ports of the cylinder, said slide valves lying respectively in contact with one surface of the cylinder and with the surface of the first slide valve that is not in contact with the cylinder wall and being adapted to move simultaneously and in opposite directions in register with the upper ports in the cylinder for covering and uncovering same through their cooperation, a linkage connected with both slide valves, an eccentric controlling said linkage for constraining the slide valves to move in opposite directions when closing the upper

series of ports in the cylinder and to operate cyclically, the cycle of operation including a long period of short oscillations while the slide valve closes the upper series of ports in the cylinder, after which the slide valves assume a high acceleration for uncovering and then covering again said upper series of ports in the cylinder while the valve moves at high speed and produces thus an opening of the upper ports with a large cross-sectional passage during a very short time, the cycle terminating with the return into the port covering position, the driving piston being adapted to cover and uncover the lower series of ports in the cylinder, a lag being provided between the uncovering of the upper series of ports and that of the lower series of ports in the cylinder.

5. In a two stroke internal combustion and the like engine, the combination of a cylinder provided at each end with two series of ports adapted respectively to serve as admission ports and as exhaust ports, the upper series of ports being provided at the upper end of the cylinder and the lower series opening substantially at the lower end of the combustion chamber in the cylinder, a driving piston adapted to reciprocate inside the cylinder between an upper dead point and a lower dead point substantially in register with the lower series of ports, two slide valves of which one is provided with two series of ports adapted to register respectively with the upper ports of the cylinder and with the lower series of ports while the other slide valve is provided with a single series of ports adapted to register with the upper series of ports of the cylinder, at least one of said slide valves lying in contacting relationship with one of the surfaces of the cylinder, a linkage connected with at least one slide valve, means associated with the linkage for constraining the two slide valves to move in opposite directions and to register simultaneously through their upper ports with the upper series of ports in the cylinder for covering and uncovering same, the cycle of operation of the slide valves including a comparatively long period of small oscillations during which the upper and lower series of ports in the cylinder are closed, following which a high acceleration leads to the uncovering and covering at a high speed of the upper series of ports in the cylinder through simultaneous registering thereof with the upper ports in both slide valves to provide a high speed opening with a large throughput area for said ports, after which the upper and lower series of ports in the cylinder are covered again, the piston cooperating with the first slide valve for controlling the lower ports in the cylinder for uncovering and covering same through a movement of the piston that is simultaneous with and in opposite direction with reference to the lower series of ports in the first slide valve, a shifting in time being provided between the uncovering of the upper and of the lower series of ports in the cylinder.

6. In an engine of the two stroke internal combustion type, the combination of at least one cylinder provided in its wall with an annular series of ports at either of its ends, a gas feeding pipe communicating with one series of ports at the upper end of the cylinder, a gas feeding pipe opening into the other series of ports at the lower end of the cylinder, a driving piston adapted to reciprocate inside the cylinder and to uncover in its downward stroke, the ports corresponding to the lower cylinder, a slide valve provided with two annular series of ports adapted to register respectively with one series of ports in the cylinder

der wall, a further slide valve coaxial with the first slide valve and provided with ports registering with the upper ports in the cylinder wall and at the same time with the corresponding ports in the first slide valve for a predetermined position of said slide valve and means controlling simultaneously the movement of the second slide valve in the same direction as the piston and that of the first slide valve in the opposite direction with a shifting in time between the simultaneous uncovering of the upper ports by the corresponding ports of the two slide valves and that of the lower ports by the piston and second slide valve.

7. In an engine of the two stroke internal combustion type, the combination of at least one cylinder provided in its wall with an annular series of ports at either of its ends, a gas feeding pipe communicating with the upper series of ports, a gas feeding pipe opening into the lower series of ports, a piston adapted to reciprocate inside the cylinder and to uncover at the end of its downward stroke, the ports corresponding to the second pipe, at least one slide valve provided with an annular series of ports and adapted to slide over the cylinder wall into and out of a position for which its ports register with a predetermined series of ports in the cylinder wall, means controlling said slide valve including an eccentric operatively connected with the piston and a link system connecting said eccentric permanently with the slide valve for causing it to sweep past the corresponding series of ports in the cylinder wall at a speed that is high between the moments of uncovering and of covering said cylinder ports while slowing down the movement of said slide valve during the periods during which the series of ports considered are out of register.

8. In an engine of the two stroke internal combustion type, the combination of at least one cylinder provided in its wall with an annular series of ports at either of its ends, a pipe communicating with the upper series of ports, a pipe opening into the lower series of ports, a piston adapted to reciprocate inside the cylinder and to uncover at the end of its downward stroke, the ports corresponding to the second pipe, at least one slide valve provided with at least one annular series of ports adapted to slide over at least one cylinder wall into and out of a position for which its ports register with a predetermined series of ports in the cylinder wall, means controlling said slide valve including a cam system operatively connected with the piston and a positively operated linkage between said cam system and the slide valves for causing them to sweep past at least one corresponding series of ports in the cylinder wall at a full speed between the moments of uncovering and of covering said cylinder ports while slowing down the movement of said slide valves during the periods during which the series of ports considered are out of register.

9. In an engine of the two stroke internal combustion type, the combination of at least one cylinder provided in its wall with an annular series of ports at either of its ends, a pipe communicating with the upper series of ports, another pipe opening into the lower series of ports, a piston adapted to reciprocate inside the cylinder and to uncover in its downward stroke the ports corresponding to the second pipe, coaxial slide valves adapted to move over one cylinder wall and having an annular series of ports adapted to register at a predetermined moment of their movements with one another and with

the ports in the cylinder wall and means controlling the movements of said slide valves in opposite directions, including at least one eccentric operatively connected with the piston and means connecting the two slide valves to move same in opposite directions and controlled positively by said cam system.

10. In an engine of the two stroke internal combustion type, the combination of at least one cylinder provided in its wall with an annular series of ports at either of its ends, a pipe communicating with the upper series of ports, another pipe opening into the lower series of ports, a piston adapted to reciprocate inside the cylinder and to uncover in its downward stroke, the ports corresponding to the second pipe, coaxial slide valves adapted to move over the cylinder wall and having an annular series of ports adapted to register at a predetermined moment of their movements with one another and with the ports in the cylinder walls and means controlling the movements of said slide valves in opposite directions including at least one eccentric operatively connected with the piston and a compensating bar connecting the two slide valves to move same in opposite directions and controlled positively by said cam system.

11. In an internal combustion engine, the combination of two coaxial slide valves defining a cylindrical chamber and provided respectively with one and with two annular series of ports, the first of which is adapted to register with that in the first slide valve, a piston adapted to reciprocate inside said cylindrical chamber and to uncover at the end of its stroke the second annular series of ports in the second slide valve and means mechanically interconnecting the piston with each of the two cylindrical members for constraining the latter to move in opposite directions with reference to the piston so as to bring the ports in the first cylindrical member into register with the second series of ports in the second slide valve at a predetermined moment with reference to the uncovering of the second series of ports in the second slide valve by the piston and two pipes communicating respectively with the first two series of ports when registering with one another and with the last series of ports when uncovered by the piston.

12. In a two stroke engine, the combination of a cylinder wall provided at each end with an annular series of ports, two pipes opening respectively into the corresponding series of ports, at least one cylindrical slide valve cooperating with said cylinder wall and of which at least one lies in direct contacting relationship with said cylinder wall, and each slide valve being provided with at least one series of ports adapted to register with the corresponding ports in the other slide valve and in the cylinder wall, a piston slidingly engaging the cylinder and valve system, mechanical means controlling positively the operation of the valves and means permanently and mechanically connecting the piston with the said mechanical means to constrain the ports in at least one slide valve to execute first slight oscillations during a comparatively long time and then to move at a very high velocity for uncovering and covering the registering ports during a very short time over a large area, the piston being adapted to cooperate in the uncovering of the lower ports with a shifting in time between the uncovering and covering of the two series of ports.

13. In a two stroke engine, the combination of a cylinder wall provided at each end with an

annular series of ports, two pipes opening respectively into the corresponding series of ports, two cylindrical slide valves cooperating with said cylinder wall and lying respectively in contacting relationship with each side of the cylinder wall and each slide valve being provided with at least one series of ports adapted to register with the corresponding ports in the other slide valve and in the cylinder wall, a piston slidably engaging the cylinder and valve system, mechanical means controlling positively the operation of the valves and means permanently and mechanically connecting the piston with the said mechanical means to constrain the ports in the slide valves to move at a very high velocity into and out of register with the corresponding cylinder wall valves, the piston being adapted to cooperate in the uncovering of the lower ports with a shifting in time between the uncovering and covering of the two series of ports.

14. In a two stroke engine, the combination of a cylinder wall provided at each end with an annular series of ports, two pipes opening respectively into the corresponding series of ports, two cylindrical slide valves cooperating with said cylinder wall and lying respectively for the first slide valve in contacting relationship with the cylinder wall and for the second slide valve with the surface of the first slide valve that is not in contact with the cylinder wall, and each slide valve being provided with at least one series of ports adapted to register with the corresponding ports in the other slide valve and in the cylinder wall, a piston slidably engaging the cylinder and valve system, mechanical means controlling positively the operation of the valves and means permanently and mechanically connecting the piston with the said mechanical means to constrain the ports in the slide valves to move at a very high velocity into and out of register with the corresponding cylinder wall valves, the piston being adapted to cooperate in the uncovering of the lower ports with a shifting in time between the uncovering and covering of the two series of ports.

15. In a two stroke engine, the combination of a cylinder wall provided at each end with an annular series of ports, two pipes opening respectively into the corresponding series of ports, at least one cylindrical slide valve cooperating with said cylinder wall and of which at least one lies in direct contacting relationship with said cylinder wall, and each slide valve being provided with at least one series of ports adapted to register with the corresponding ports in the other slide valve and in the cylinder wall, a piston slidably engaging the cylinder and valve system, mechanical means controlling positively the operation of the valves and means permanently and mechanically connecting the piston with the said mechanical means to constrain the upper ports of the two slide valves to move simultaneously in opposite directions in front of the upper ports of the cylinder for covering and uncovering same at a high speed, the piston being adapted to cooperate in the uncovering of the lower ports with a shifting in time between the uncovering and covering of the two series of ports.

16. In a two stroke engine, the combination of a cylinder wall provided at each end with an annular series of ports, two pipes opening respectively into the corresponding series of ports, two cylindrical slide valves cooperating with said cylinder wall and lying respectively in contacting relationship with each side of the cylinder wall, and each slide valve being provided with at least

one series of ports adapted to register with the corresponding ports in the other slide valve and in the cylinder wall, a piston slidably engaging the cylinder and valve system, mechanical means controlling positively the operation of the valves and means permanently and mechanically connecting the piston with the said mechanical means to constrain the upper ports of the two slide valves to move simultaneously in opposite directions in front of the upper ports of the cylinder for covering and uncovering same at a high speed, the piston being adapted to cooperate in the uncovering of the lower ports with a shifting in time between the uncovering and covering of the two series of ports.

17. In a two stroke engine, the combination of a cylinder wall provided at each end with an annular series of ports, two pipes opening into the corresponding series of ports, two cylindrical slide valves cooperating with said cylinder wall and lying respectively for the first slide valve in contacting relationship with the cylinder wall and for the second slide valve with the surface of the first slide valve that is not in contact with the cylinder wall, and each slide valve being provided with at least one series of ports adapted to register with the corresponding ports in the other slide valve and in the cylinder wall, a piston slidably engaging the cylinder and valve system, mechanical means controlling positively the operation of the valves and means permanently and mechanically connecting the piston with the said mechanical means to constrain the upper ports of the slide valves to move simultaneously in opposite directions in front of the upper ports of the cylinder for covering and uncovering same at a high speed, the piston being adapted to cooperate in the uncovering of the lower ports with a shifting in time between the uncovering and covering of the two series of ports.

18. In a two stroke engine, the combination of a cylinder wall provided at each end with an annular series of ports, two pipes opening into the corresponding series of ports, two cylindrical slide valves cooperating with said cylinder wall and of which at least one lies in direct contacting relationship with said cylinder wall, and each slide valve being provided with at least one series of ports adapted to register with the corresponding ports in the other slide valve and in the cylinder wall, a piston slidably engaging the cylinder and valve system, an eccentric controlling positively the operation of the valves and means permanently and mechanically connecting the piston with the said eccentric to constrain the ports in the slide valve to move at a very high velocity into and out of register with the corresponding cylinder wall valves, the piston being adapted to cooperate in the uncovering of the lower ports with a shifting in time between the uncovering and covering of the two series of ports.

19. In a two stroke engine, the combination of a cylinder wall provided at each end with an annular series of ports, two pipes opening respectively into the corresponding series of ports, two cylindrical slide valves cooperating with said cylinder wall and of which at least one lies in direct contacting relationship with said cylinder wall, and each slide valve being provided with at least one series of ports adapted to register with the corresponding ports in the other slide valve and in the cylinder wall, a piston slidably engaging the cylinder and valve system, a cam

13

system controlling positively the operation of the valves and means permanently and mechanically connecting the piston with the said cam system to constrain the ports in the slide valves to move at a very high velocity into and out of register with the corresponding cylinder wall valves, the piston being adapted to cooperate in the uncovering of the lower ports with a shifting in time between the uncovering and covering of the two series of ports.
